UNITED STATES PATENT OFFICE

90,688

DESIGN FOR A CHOCOLATE BAR

Leicester H. Sherrill, Larchmont, N. Y., assignor to General Foods Corporation, New York, N. Y., a corporation of Delaware

Application January 4, 1933. Serial No. 46,728

Term of patent 14 years

To all whom it may concern:

Be it known that I, LEICESTER H. SHERRILL, a citizen of the United States, residing at Larchmont, county of Westchester, State of New York, have invented a new, original, and ornamental Design for a Chocolate Bar, of which the following is a specification, reference being had to the accompanying drawing, forming part thereof.

Fig. 1 is a top view of the bar
Fig. 2 is a side view thereof, and
Fig. 3 is an end view.

I claim:

The ornamental design for a chocolate bar, as shown.

LEICESTER H. SHERRILL.
